WING FLAP

Temple N. Joyce, Arnold, Md., assignor to Zap Development Corporation, Baltimore, Md., a corporation of Delaware

Application August 14, 1937, Serial No. 159,158

3 Claims. (Cl. 244—42)

My invention relates to an airplane construction, and more particularly to a flap construction adapted to change the flow around the surface of an airfoil.

An object of my invention is to obtain a balancing effect during the time of lowering the flap.

A further object of my invention is to provide a slot effect between the flap and the airfoil which gives an increased efficiency to the action of the flap by producing desirable phenomena in the flow of air back of the main airfoil.

A further object is to decrease the turbulence back of the main airfoil and thereby reduce tail buffeting which is so common in certain flap installations.

With these and other objects in view, which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

Figure 1 is a top plan view of an airplane equipped with my flap construction;

Fig. 2 is a fragmentary perspective view of the operating mechanism for my wing flaps;

Fig. 3 is a sectional view taken through the rear of a wing showing my flap construction with the flap in the up or closed position;

Fig. 4 is a view similar to Figure 3, showing the flap in the down position;

Fig. 5 is a detail sectional view taken along the line 5—5 of Figure 4, looking in the direction of the arrows;

Fig. 6 is a diagrammatic view showing the geometry of movement of the parts in lowering the flap into operative position.

Referring to the drawings, I have shown an airplane 1 having a motor 2, fuselage 3, wings 4, ailerons 5 mounted above the wings, and flaps 6 mounted below the wings near the trailing edge.

Each wing 4 has a rear spar 7, and is provided with a recess 8 near its trailing edge in which is

mounted the flap 6. The flap 6 is preferably made of sheet metal and is provided with a lower surface 9 and an upper surface 10 which are attached to U-bracing members 11. Recesses 12 are formed in the upper surface of the flap in which are located pivots 13 and 14. To each of the pivots 13 are fastened cranks 15 which are attached at their upper ends to an operating shaft 16. The operating shaft 16 serves as a pivot for the upper ends of the cranks 15. On the pivots 14 are mounted links 17 whose upper ends are pivoted at points 18 in the wing construction.

The hollow shaft 16 is provided with a worm gear 19 which meshes with a worm 20 affixed to a shaft 21 which is journaled at 22 and 23 in the fuselage 3. The shaft 21 is operated through meshing beveled gears 24, one of which is rotated by means of an operating handle 25. The operating handle 25 is located near the pilot's seat so that he can, through rotating the handle 25, rotate the hollow shaft 16 to move the flap into either its operative position, as shown in Figure 3, or a lower position wherein the flap is extended and effects the air flow around a wing.

Each wing 4, at its trailing edge, has a series of horns 26 on which are mounted ailerons 5 which are controlled by rods 27 connected to suitable control members mounted in the fuselage.

When the flap is in its Fig. 3 raised position, the lower surface 9 of the flap forms, in effect, a continuation of the rear portion of the associated wing undersurface so that the air will flow smoothly across the wing undersurface. By preference, the flap does not project rearwardly beyond the trailing edge of the wing and is located in the concave recess 8 formed below the wing uppersurface whereby the smooth flowing lines of the wing uppersurface are not broken by the flap.

It is to be noted that with the flap in the position shown in Figure 4, there is provided a slot between the nose 28 of the flap and the recess 8 formed in the lower surface of the wing 4. This slot gives a desirable slot and balancing effect which is highly desirable and increases not only the efficiency of the flap itself, but also is of great aid in operating the flap and moving it from the inoperative to the operative position.

It is to be noted that the flap in its movement from inoperative to operative position at all times has its rear edge substantially directly below the rear edge of the main airfoil. Another

way of stating this is to say that the flap in all its extended positions has its trailing edge substantially in the locus of perpendiculars to the datum lines for the wing sections which pass through the trailing edges of the wing. This type of flap, in combination with the slot effect presents advantages in operation and performance which exceed in desirable features the operative characteristics of other types of flap.

10 The geometry of the operation of the various parts can be seen from an inspection of Figure 6. Figure 6 illustrates that the nose of the flap

15 opens up a definite slot in its downward movement until it reaches a point at which the nose of the flap closes the slot between the nose of the flap and the lower surface of the wing.

While I have shown and described the preferred embodiment of my invention, I wish it to be understood that I do not confine myself to 20 the precise details of construction herein set forth by way of illustration, as it is apparent that many changes and variations may be made therein, by those skilled in the art, without departing from the spirit of the invention or exceeding the 25 scope of the appended claims.

I claim:

1. A flap construction for an airplane compris-

ing an airfoil, a flap adapted to be extended below the airfoil, the trailing edges of said flap in all operative positions lying substantially in the locus of perpendiculars to the datum lines for the airfoil sections at the trailing edge of the 5 airfoil sections, and guide means for the flap which cause the nose of the flap to open up a slot for the passage of air over the nose and between the flap and airfoil while the flap is being extended downwardly and closes the slot when 10 the flap is completely lowered.

2. In an airplane, a wing, a flap adapted to be extended below the wing, links connecting the flap to the wing so that when the flap is being extended downwardly, an air passage is formed 15 between the flap and the wing, said air passage being closed when the flap is completely lowered.

3. In an airplane, a wing, a flap adapted to be extended below the wing, connecting guide means between the flap and the wing such that when the 20 flap is being extended downwardly, an air passage is formed between the flap and the wing, said air passage being closed by the flap when fully lowered.

TEMPLE N. JOYCE. 27
